Fig. 1

Fig. 2

Fig. 3

Fig. 5

Fig. 4

FIG. 1 is a side elevational view of a housing for garage door operator embodying my improved design;

FIG. 2 is a front view thereof;

FIG. 3 is a bottom view thereof;

FIG. 4 is a top view thereof; and

FIG. 5 is a perspective view thereof shown on a smaller scale than that of the other figures.

The other side view is substantially identical to the side shown in FIG. 1.

The rear view is substantially identical to the front view shown in FIG. 2.

The broken lines in FIGS. 1, 2, 3, 4 and 5 indicate environmental structure, included for illustration purposes.

I claim:

The ornamental design for a housing for garage door operator, as shown and described.
